[57] CLAIM

The ornamental design for an eyeglass case, as shown and described.

DESCRIPTION

FIG. 1 is a front elevational view of an eyeglass case showing my new design;

FIG. 2 is a right side elevational view thereof, the left side being a mirror image;
FIG. 3 is a rear elevational view thereof;
FIG. 4 is a top plan view thereof;
FIG. 5 is a bottom plan view thereof;
FIG. 6 is a rear elevational view of an alternate embodiment of the design shown in FIG. 1;
FIG. 7 is a right side elevational view thereof, the left side being a mirror image;
FIG. 8 is a top plan view of FIG. 6;
FIG. 9 is a bottom plan view of FIG. 6;
FIG. 10 is a front elevational view of a second embodiment of the design shown in FIG. 1;
FIG. 11 is a front elevational view of FIG. 10, the flap being shown in a fastened position;
FIG. 12 is a right side elevational view of FIG. 11, the left side being a mirror image;
FIG. 13 is a top plan view of FIG. 11;
FIG. 14 is a bottom plan view of FIG. 11;
FIG. 15 is a rear elevational view of FIG. 11;
FIG. 16 is a front elevational view of a third embodiment of the design shown in FIG. 1;
FIG. 17 is a right side elevational view of FIG. 16, the left side being a mirror image;
FIG. 18 is a rear elevational view of FIG. 16;
FIG. 19 is a top plan view of FIG. 16;
FIG. 20 is a bottom plan view of FIG. 16;
FIG. 21 is a front elevational view of a fourth embodiment of the design shown in FIG. 1;
FIG. 22 is a right side elevational view of FIG. 21, the left side being a mirror image;
FIG. 23 is a rear elevational view of FIG. 21;
FIG. 24 is a top plan view of FIG. 21; and,
FIG. 25 is a bottom plan view of FIG. 21.
The broken lines shown in FIGS. 21 and 23 are understood to represent conventional stitching.
